Primary Examiner — Rachel A. Voorhies*Assistant Examiner* — Benjamin D. Wannemacher(74) *Attorney, Agent, or Firm* — Greenberg Traurig, LLP(57) **CLAIM**

The ornamental design for a power tube expander as shown and described.

DESCRIPTION

FIG. 1 is a bottom plan view of my design of a power tube expander.

FIG. 2 is a perspective view thereof.

FIG. 3 is a front elevation view thereof.

FIG. 4 is a right side elevation view thereof.

FIG. 5 is a back elevation view thereof.

FIG. 6 is a left side elevation view thereof.

FIG. 7 is a top plan view thereof; and,

FIG. 8 is an enlarged view of the area labeled 8 shown in FIG. 5.

The dash-dot broken line in FIG. 5 illustrates a boundary of the enlarged view in FIG. 8 and forms no part of the claimed design.
